UNITED STATES PATENT OFFICE.

HUGO HAAGE, OF BERLIN-CHARLOTTENBURG, GERMANY, ASSIGNOR TO SIEMENS-SCHUCKERTWERKE GESELLSCHAFT MIT BESCHRÄNKTER HAFTUNG, OF SIEMENS-STADT, NEAR BERLIN, GERMANY, A CORPORATION OF GERMANY.

ELECTRIC COMMUTATOR.

Application filed January 23, 1922. Serial No. 531,202.

To all whom it may concern:

Be it known that I, HUGO HAAGE, a citizen of the German Empire, residing at Berlin-Charlottenburg, Germany, have invented certain new and useful Improvements in Electric Commutators, of which the following is a specification.

In electric machinery, commutators of rather great length act detrimentally on the shaft, on which they are mounted, owing to the expansion of their segments. Various means have already been proposed to overcome this drawback.

The present invention relates to such means, which are of very simple and cheap construction.

According to the invention, the commutator is mounted on its shaft with a comparatively short part of its inner length only, while the remaining parts of its inner length are freely suspended in radial direction around said shaft, any deformations of the commutator having thus no action on the shaft.

In the accompanying drawing, Figs. 1 and 2 are longitudinal sections of two different forms of construction showing how the invention can be reduced to practice.

Referring to Fig. 1:—The segments *s* of the commutator *a* are provided on their inner sides with an axially short inward projection *v*, at which they are mounted on a tapered portion of the shaft *w* by means of an intermediary insulation *i*, a threaded collar *b* locking the commutator in place by means of a spacing bushing *z* and a pressure-ring *r*. Slip-rings *d* serve to keep the segments in place in radial directions. The ends of the commutator extending beyond portion *v* are freely suspended around said shaft, an insulation *e* with a metal cover *m* being provided on the inner sides of said protruding ends and held in place by any suitable means, for instance by corrugations as shown, so as to prevent current leakage at said inner sides, which might occur through dust accumulating on the free spaces between said freely suspended commutator ends and said shaft.

Thus, the segments of the commutator

can freely expand in axial and radial directions, without detrimentally acting on the shaft.

Referring to Fig. 2:—The commutator *a* comprises here a separate inner sleeve *c*, on which the segments are located by means of an insulation *o* and secured by means of a pressure-ring *k* and a fastening-collar *u*. This sleeve is mounted on a tapered portion of the shaft *w* with a comparatively short part of its length only and secured thereon by means of a spacing bushing *z* and a threaded collar *b*.

In this construction, radial expansions of the segments can be transmitted to the sleeve *c* but not to the shaft *w*. A resilient or springy member *f* is interposed between the pressure-ring *k* and the fastening-collar *u*, for the purpose of permitting an axial expansion of said segments and preventing a deformation of the latter when being pressed together in axial direction.

The improved arrangement, besides preventing any detrimental action on the shaft by a deformation of the commutator, has the further advantage that, vice versa, also the shaft can get deformed without thereby disturbing the commutator.

What I claim, is:—

1. In combination, a shaft, and a commutator mounted with a comparatively short part of its inner length on said shaft, the remaining parts of the length being freely suspended around said shaft, substantially as and for the purpose set forth. 80

2. In combination, a shaft, a sleeve of insulation around said shaft and commutator segments mounted with a comparatively short inner part of their length on said insulation, the remaining parts being freely suspended around said shaft. 90

3. In combination, a shaft, and a commutator insulatedly mounted with a comparatively short part of its length on said shaft, the remaining parts being freely suspended around said shaft, and an insulation on the inner sides of said freely suspended parts facing said shaft, substantially as and for the purpose set forth. 95

4. In an arrangement of the type speci- 100

fied in claim 3, a metal cover on said insulation, substantially as set forth.

5. In combination, a shaft, a commutator insulatedly mounted with a comparatively short part of its length on said shaft, the remaining parts being freely suspended around said shaft, and an insulation with a

metal cover on the inner sides of said freely suspended parts facing said shaft secured thereon by corrugations, substantially as 10 and for the purpose set forth.

In testimony whereof I affix my signature.

HUGO HAAGE.
